UNITED STATES PATENT OFFICE.

LUTHER WINTHROP PUFFER, OF MEDFORD, MASSACHUSETTS.

VALVE FOR GENERATORS.

SPECIFICATION forming part of Letters Patent No. 363,763, dated May 24, 1887.

Application filed January 22, 1885. Serial No. 153,626. (No model.)

To all whom it may concern:

Be it known that I, LUTHER WINTHROP PUFFER, a citizen of the United States, residing at Medford, in the county of Middlesex and State of Massachusetts, have invented certain new and useful Improvements in Valves for Generators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the discharge-valves of generators or other vessels for the manufacture of carbonic-acid or analogous gases—that is to say, valves for emptying such generators of their spent products, which in the manufacture of carbonic-acid gas for aerated waters and other purposes consist largely of marble-dust, vitriol, and water.

One feature of my invention is in attaching to the valve and beyond its seat an implement adapted to rotate with the valve as it is turned when the latter is in the act of opening or closing, whereby the sedimentary spent particles are thoroughly broken up and disturbed. Thus when the valve is opened they are free and loose, and in readiness to pass off with the discharge contents of the generator. By introducing this feature the valve, in lieu of being located at the opening or orifice leading from the generator, is seated upon the lower extremity of the bung connecting the valve-case with its generator.

My invention further embraces mechanical details of construction for permitting of tightening of the cap of the stuffing-box in the manner of constructing and attaching the valve-case to the body of the generator, and in other minor features, to be hereinafter described. This manner of connecting the valve-case to the generator contains one feature which I consider of much importance, and it will readily be seen that, owing to the position of the valve with respect to the bung upon which it is seated no direct pressure from the generator is ever brought upon the valve-case.

The drawings accompanying this specification represent, in Figure 1, a vertical section of

a valve containing my improvements. Figs. 2 and 3 represent modified forms of the bung and different seating of the valve. Fig. 4 shows a still further modification. Fig. 5 represents the valve seated upon the inner extremity of the bushing, and Fig. 6 is a plan of the agitator to be attached to the valve. Fig. 7 is a plan of the inner packing-nut and the wrench for securing it in position.

In Fig. 1 of such drawings the lower part of the shell of the generator is shown at A, and the anti-corrosive lining thereof at B, a circular opening, C, being formed in the bottom A, to permit of insertion of a tubular plug or "bung," D, as it is usually termed in these generators. This bung or tubular plug has a peripheral screw-thread, a, upon its lower part, which is adapted to screw into a female thread, b, in the mouth c of the upper part of the valve-case. The bung D is inserted in the opening C, and its upper end is formed with an outstanding peripheral ledge d, which overlaps the edge of the mouth of the opening C, and is secured in place by a mass of solder, e, floated between such ledge and a swell, f, in the lining B; or, for additional security, a nut, E, may be screwed upon the threaded shank a of the bung and against the bottom of the generator, as shown in the drawings.

The valve-seat is shown at g in Fig. 1 as formed upon the lower or outer extremity of the bung D. By this means all pressure direct from the generator is removed from the valve-case, while at the same time less movement of the valve is required in order to discharge the contents of the generator. Since the bung D is open, the sedimentary spent particles in the generator are free to collect and lodge therein, caking together, and making it difficult to empty the vessel easily. To obviate this difficulty, I have disposed an agitator or clearer, A', which is secured to the valve between the outer and the inner extremity of the bung. This agitator extends the entire length of said bung, and is provided with a head, d', formed with two radial arms, the distance from the tip of one arm to the tip of the other being about equal to the diameter of its inclosing-bung. To compel rotation of this agitator or clearer with the valve G, I have connected it with a screw-thread and

pin. Thus upon turning the valve-stem upon its thread the valve is forced to rotate, carrying with it the agitator A', the radial arms of which disintegrate and break up the mass of spent particles which have collected within the bore of the bung. Thus when the valve is opened, the particles are free to pass out with the refuse or discharge contents of the generator.

In Figs. 2 and 3 the valve seat is an integral part of the bung, consisting in Fig. 3 of a simple annular interior shoulder, *g*, and in Fig. 2 of an outward extension, *g'*, of such a shoulder. In the latter case this supplementary ledge or extension *g'* is concentric with the valve-rod, and leaves a thin annular open space between it and the inner wall of the bung. The ledge *g*, Fig. 2, is on the interior of the shallow mouth *F* of the bung and as near the upper ledge of the latter as is consistent with proper strength, and the mouth *F* below the valve increases in diameter as it descends, in order, as before stated, to prevent lodgment of the spent products of the generator after the valve has been opened; or, in lieu of making the valve-seat an integral part of the bung, as shown, it may be an independent ring screwed into the mouth of the bung from above, as shown at *N* in Fig. 4 of the drawings, which is a section of the parts. The valve, as shown at *G*, is a circular disk secured horizontally to the upper end of a vertical stem, *H*, said valve closing upward against the seat *g*.

The lower part of the valve-stem *H* is peripherally screw-threaded, and screws through a boss, *I*, in the lower part of the valve-case *J*, a hand-wheel, *K*, being secured to the lower extremity of said stem. The valve-chamber *h* begins to enlarge immediately below the valve to afford ample means of escape for the contents of the generator.

The stuffing-box about the valve-stem is shown at *L* as a recessed boss erected upon the bottom of the valve-chamber, the cap or cover of such box being shown at *i*. This stuffing-box effectually protects the screw-thread of the valve-stem by preventing access to such thread of the gritty material escaping from the generator. The valve is to be inserted in place and the cap *i* screwed down from the open mouth *P* of the valve-case.

To enable the cap of the stuffing-box *L* to be raised or lowered as occasion requires, I form a series of teeth, *j*, *j*, &c., upon the periphery of the upper part of such caps, and I employ a spanner (shown at *O*) to engage these teeth; or the periphery of the caps may have a series of peripheral pockets, or be otherwise roughened, to form a grip for a wrench or spanner.

To provide an approach to the stuffing-box, to permit of introducing the spanner, or to inspect or refill such box, the outlet *P* of the valve-case is placed to one side of the latter and opposite the stuffing-box. By placing the valve and valve-seat immediately at the bot-

tom of the generator, as explained, no considerable amount of sedimentary or solid matter can remain over the valve-level, while, as hereinbefore stated, the contents of the generator exert their full pressure directly upon the outlet, and the full escape of such contents upon the opening of the valve is insured. By placing the stuffing-box within the valve-case in lieu of upon the outside, as heretofore universally practiced, the pressure of the escaping contents of the generator tends to tighten, rather than to loosen, its cap, and in addition the screw-thread of the valve-stem is protected, as before stated.

In Fig. 2 of the drawings the screw-thread of the valve-stem is protected from the contents of the generator by means of a tubular boss, *l*, depending from the valve and surrounding the valve-stem, this boss telescoping with a tubular teat, *m*, erected upon the bottom of the valve case and closely fitting the valve stem. In this case the stuffing-box, if one is needed, may be placed outside of the valve-case, as shown in said Fig. 2.

In Fig. 3 of the drawings the bung *D* has an interior peripheral screw-thread, *o*, to receive a tubular neck, *p*, cast upon the upper part of the valve-case, the valve-seat in this instance being an interior peripheral ledge, *q*, formed in the mouth of the said neck *p*. In this connection it would be well to introduce a packing-ring, *r*, between the lower end of the bung, and a shoulder, *s*, cast upon the base of the neck *p*, although this packing will not be found absolutely necessary.

By placing the valve-seat at the extreme upper part of the valve-case, as shown, such case and its various joints are removed and relieved from the pressure upon the interior of the generator; hence the case may be cast of less weight, and danger of leakage of its joints prevented.

In Fig. 1 I have shown the valve seated upon the lower end of the bung, and since I have provided the valve with the agitator before described the objections which formerly occurred, owing to the spent particles collecting and solidifying within the bung and upon the top of the valve, and thereby preventing discharge, are entirely removed. Upon movement of the valve similar motion is conveyed to the agitator, and the result is that the particles are disturbed and loosened simultaneously upon the removal of the valve from its seat. One advantage in this position of the valve is that a small movement of the valve effects a full discharge, since the valve at once withdraws into the enlarged portion of the valve-case.

Although I have shown a valve having its valve-seat at the extreme upper part of the case and forming an integral part of the latter, in lieu of its being on the bung, as in Fig. 1, with the valve closing upward against such seat, still I do not desire to be limited to that precise method of operating this valve, inasmuch as there are some advantages to be

gained by having the valve close and rest upon the top or interior edge of the valve-case, as shown in Fig. 5. Upon referring to Fig. 3 it is evident, in operating the valve to empty the generator, that it will be necessary to retract the valve from its seat, through the neck of the valve-case, until it has reached the enlarged chamber, forming part of said case, before a full and free vent can be obtained 10 through the discharge-port; hence it is necessary for the operator to change the position of the valve to a considerable extent. On the other hand, in case the valve is above the valve-seat, movement of the valve-stem needs 15 to be but very small to open the port and effect a full discharge, since the valve moves upward into the interior of the generator, and there is no contracted neck through which the valve passes, and which prevents free and full 20 vent through the port upon a very slight movement of said valve.

A second advantage attained by the use of the valve in the position as shown in Fig. 5 is that with the same size valve-case a larger discharge-port can be employed, since in the instance where the valve is closed upward against the valve-case the annular lip *g* has to be made of sufficient depth to give the valve a proper bearing-surface, and the discharge-orifice is 30 contracted thereby. On the other hand, the thickness of the valve-case proper affords a suitable bearing-surface or seat for the valve, and the annular projection *g* may be made very much smaller, or, if so desired, removed entirely, whereby the discharge-port is accordingly enlarged and an increased delivery secured, which is of much advantage where the object to be obtained is speed in emptying the 35 vessel of its contents.

40 In each of the forms shown the bung serves as an outlet-passage, and also presents a valve-seat for the discharge-valve.

I claim--

1. In a generator, the combination, with the 45 valve and valve-case, of a bung secured to the

generator and adapted to engage with said valve-case and be closed by the valve, substantially as herein set forth.

2. A valve for generators, composed of the valve-case *J*, united with a hollow bung, *D*, 50 secured to the generator *A*, the latter being closed by the valve *F*, seating on the bung, substantially as described.

3. A valve for soda-water apparatus, which consists of a tubular bung secured to the outlet of a closed vessel, in combination with a valve and valve-case, whereby the mouth of the bung constitutes the seat of the valve, substantially as herein shown. 55

4. The tubular bung constituting means for 60 attaching the valve-case to the generator and for closing the outlet of such generator, in combination with the valve and valve-case, whereby packing between the latter and the generator is dispensed with, substantially as described. 65

5. The tubular bung with the valve-seat formed interiorly upon it, and the outer peripheral ledge formed upon the bung to secure it to the generator, substantially as shown and described. 70

6. In combination with bung *D*, forming an outlet-passage from the generator and also a seat for the discharge-valve, the valve-disk *G*, and the agitator *A'*, the latter being provided with two radial arms, which extend across the 75 interior of said bung, substantially as set forth.

7. The combination of the stuffing-box and its cap, having an indented periphery, with a spanner adapted to take hold of said periphery, and the inclosing valve-case having its outlet-opening situated opposite such stuffing-box to allow said cap and box to be reached from outside of said case, substantially as set forth. 80

In testimony whereof I affix my signature in presence of two witnesses.
